UNITED STATES PATENT OFFICE.

ROBERT J. THOMPSON, OF HARRISBURG, PENNSYLVANIA.

INTERNAL-COMBUSTION ENGINE.

Application filed January 13, 1927 Serial No. 160,934.

The present invention relates to rotary valve mechanisms for internal combustion engines of the type disclosed in my application, Serial No. 60,902, filed October 6, 1925.

5 One of the principal objects is to provide means for more effectively sealing the passageways of the valve shaft against leakage and to insure more effective packing joints at the intake and exhaust passages of the 10 engine.

In the accompanying drawings:—

Figure 1 is a vertical sectional view through an engine illustrating the valve mechanism in elevation,

15 Figure 2 is a cross sectional view taken on the line 2—2 of Figure 1,

Figure 3 is a detail cross sectional view on an enlarged scale through the valve,

20 Figure 4 is a detail perspective view of a portion of the shaft, showing one of the pockets,

Figure 5 is a view in elevation showing the ring expanding means,

25 Figure 6 is a perspective view of one of the filling blocks and the packing ring mounted thereon,

Figure 7 is a perspective view of one of the filling blocks detached,

30 Figure 8 is a perspective view of an expanding wedge.

In the embodiment disclosed, an engine block is shown, comprising a cylinder member 9 containing a plurality of piston chambers 10. Mounted to reciprocate in these 35 chambers are pistons 11. It will be understood that this structure may be of any well-known or desired type.

On the cylinder member is fixed a head 12, in which is formed a valve chamber 13 extending over and common to all the piston chambers 10. This valve chamber 13 is in communication with the various piston chambers 10 by means of ports 14, and in the same planes with the said ports, but in opposite 40 sides of the head block, are formed intake or supply ports 15 and exhaust-permitting ports 16.

A rotary shaft 17 extends through the chamber 13 and is driven by any suitable 50 means. This shaft is provided with a series of transversely disposed recesses or pockets 18, that are located in the same planes with the ports 14, 15 and 16. In the recesses or pockets 18 are fitted detachable filler blocks 55 19 that fill the pockets and have their outer

surfaces curved to conform to the curvature of the shaft. Each of these blocks is provided with a passageway 20, that extends across it and opens through its outer side.

Surrounding the shaft 17 and covering the 60 blocks 19 are packing rings 21, preferably of spring material and split. These rings are each secured at an intermediate point, as indicated at 23, to its block, the ring being such that a continuous portion extends over 65 the passageway 20. The terminal faces of the ring are designated 24, and are convergently disposed, as clearly shown in Figure 6. Between said end faces and slidably engaging the same is a wedge block 25 tapered to fit the 70 space between the end faces 24. A bridge piece 26, resting against one end of the ring and bridging the narrower end of the space has passing through it a headed stem 27 that is threaded into the narrower end of the 75 wedge 25. A coiled spring 28 is interposed between the head of the stem 27 and the bridge piece, and inasmuch as the adjacent end of the wedge is normally spaced from the bridge piece, this spring operates to draw the 80 wedge into the space between the ends of the rings and thus serves to expand said ring.

The portion of the ring covering the passageway 20 is furthermore provided with ports 29 that are in communication with the passageways 20 of the blocks, and these ports 29 are so disposed that they move into and out of register with the ports 14, 15, and 16 of the piston chambers, so as to alternately afford communication through the passageways 20, between the ports 14 and 15 and between the ports 14 and 16 as the shaft rotates.

With this construction, it will be evident that as the shaft 17 is rotated in synchronism 95 with the movements of the pistons, the supply ports 15 will be brought into communication with the ports 14 by the passageways 20 and supplies of fuel thus enter the piston chambers 10 in proper order. After the explosions take place the ports 14 will be brought into communication with the exhaust permitting ports 16, and allow the escape of the 100 exhaust gases.

The rings 21 will fit the valve chamber 105 walls, even though the shaft is not entirely true and accurate, and the blocks 19 will accommodate themselves to any reasonable change in the ring. They furthermore act as anchors for the rings, and in addition any 110

block can be readily replaced if necessary. Furthermore the blocks can be individually shaped more easily than would be the drilling and milling of the shaft itself.

5 In this construction a practical rotary valve is provided in which a relatively small amount of friction surface is necessary. Moreover this is divided up so that it is at the points where proper resistance is needed 10 to the force of the exploding charges. The securing of a continuous portion of each packing ring over the underlying passageway 20 makes a rigid structure of this portion, while the expanding wedge serves to insure a proper packing fit of the ring with 15 the piston chamber wall.

From the foregoing, it is thought that the construction, operation and many advantages 20 of the herein described invention will be apparent to those skilled in the art without further description, and it will be understood that various changes in the size, shape, proportion and minor details of construction may be resorted to without departing from 25 the spirit or sacrificing any of the advantages of the invention.

What I claim is:

1. A rotary valve for internal combustion engines, including a rotary carrier shaft, a 30 split ring surrounding the shaft and having a port for the passage of actuating fluid, and means interposed between the ends of the ring for expanding it, said means filling the space between said ends irrespective of the 35 amount of expansion of the ring created by said means.

2. A rotary valve for internal combustion engines, including a rotary carrier shaft, a 40 split packing ring on the shaft, a wedge interposed between the ends of the ring, and yielding means for causing the wedge to move in a direction to expand the ring.

3. A rotary valve for internal combustion engines, including a rotary carrier shaft, a 45 split packing ring having spaced ends provided with convergently disposed terminal faces, a wedge interposed between said faces, and a spring device connected to the smaller end of the wedge for automatically drawing the wedge between the ends of the ring.

50 4. A rotary valve for internal combustion engines, including a rotary carrier shaft, a split packing ring having spaced ends provided with convergently disposed terminal faces, a wedge interposed between said faces, a bridge piece across the narrower end of the space between the ends of the ring, a stem projecting from the smaller end of the wedge and through the bridge piece, and

5 a spring on the stem bearing against the 60 bridge piece.

5. A rotary valve for internal combustion engines, including a rotary carrier shaft having a fluid passageway, and a ring surrounding the shaft and having a continuous portion 65 covering the passageway and provided with spaced ports that communicate with the passageway, said ring having a split portion at one side of both ports and passageway. 70

6. In an internal combustion engine, the combination with a cylinder member having a plurality of piston chambers, of a valve chamber common to the piston chambers and having ports in communication therewith, a 75 rotary shaft having pockets therein aligned with the ports, blocks in said pockets having passageways, split rings secured to the blocks and embracing the same and the shaft, 80 said rings having continuous portions covering the passageways and provided with ports that move into and out of communication with the piston chamber ports, said valve chamber also having intake and exhaust permitting ports with which the ring ports communicate, wedges between the ends of the 85 rings for expanding them against the piston chamber walls, and springs acting on the wedges to cause them to exert expanding pressure on the rings. 90

7. A rotary valve for internal combustion engines including a valve casing having a fluid port, a rotary carrier shaft in the casing, a split spring ring embracing the shaft and rotatable therewith, said ring having 95 spaced ports opening through its periphery and having communication with each other within the ring, said ports successively moving into and out of communication with the casing port on the rotation of the shaft and 100 ring.

8. In an internal combustion engine, the combination with a cylinder member having a piston chamber, and a piston therein, of a valve chamber having a port in communication with the piston chamber and a supply port and an exhaust port, a rotary shaft in the valve chamber having a passageway, and a ring surrounding the shaft and covering the passageway and having ports in spaced relation opening through its periphery and being in communication with said passageway, said ports of the ring being movable to positions to establish communication between the ports of the valve chamber. 110 105 115

In testimony whereof, I affix my signature.

ROBERT J. THOMPSON.
